(57) **CLAIM**

The ornamental design for a terminal for storage battery, as shown and described.

DESCRIPTION

FIG. 1 is a perspective view of a terminal for storage battery, showing the new design;

FIG. 2 is a front elevational view of the terminal for storage battery;

FIG. 3 is a rear elevational view of the terminal for storage battery;

FIG. 4 is a right-side elevational view of the terminal for storage battery;

FIG. 5 is a left-side elevational view of the terminal for storage battery.

FIG. 6 is a top plan view of the terminal for storage battery; and,

FIG. 7 is a bottom plan view of the terminal for storage battery.
